W. B. LONG ET AL

FEEDING MECHANISM FOR STOCKING SEAMING MACHINES

Filed Sept. 30, 1925

UNITED STATES PATENT OFFICE.

WILLIAM B. LONG, OF CHICAGO, AND LOUIS SLIWA, OF CICERO, ILLINOIS, ASSIGNORS
TO UNION SPECIAL MACHINE COMPANY, OF CHICAGO, ILLINOIS, A CORPORATION
OF ILLINOIS.

FEEDING MECHANISM FOR STOCKING-SEAMING MACHINES.

Application filed September 30, 1925. Serial No. 59,743.

The invention relates to new and useful improvements in feeding mechanisms for stocking seaming machines, and more particularly to a machine of the cup feed type. Prior to this invention, intermittently operating clutching devices have been used for stepping the feed cups of a stocking seaming machine so as to feed the material being stitched, stitch lengths. Considerable difficulty, however, has been experienced in using the present type of clutch feeds for this purpose, particularly in high speed machines, for the reason that the gripping members of the clutch do not operate quick enough to grip and turn the feed cup a full stitch length, and also grip and hold the feed cup from retrograde movement. This has been caused in part by wear of the parts and in part by the slow action of spring means used for holding the clutch dogs in proper position to cause the moving part to be gripped or clutched to the part to be moved.

An object of the present invention is to provide a roller clutch device for turning the feed cup which is so constructed that the wear on the parts which are clutched together, and also on the rollers which cause said parts to be clutched together, with a construction which insures that the point of gripping contact between the members shifts, so that the wear is distributed throughout the entire surface of the roller and along the surface of the part which forces the roller into gripping contact with the clutch drum and thereby turns the drum.

A further object of the invention is to provide a spring lever means for forcing the feed rollers into contact with the surface of the clutch drum, which spring lever means can be made sufficiently strong to insure a quick movement of the roller.

These and other objects will in part be obvious and will in part be hereinafter more fully disclosed.

In the drawings which show by way of illustration one embodiment of the invention—

Fig. 1 is a view partly in section and partly in side elevation of the inner feed cup operating mechanism;

Fig. 2 is a horizontal sectional view directly above the clutch drum, looking down.

Fig. 3 is a bottom plan view of the operating mechanism for the inner feed cup with a portion of the clutch plate broken away, and

Fig. 4 is a view partly in side elevation and partly in section of the triangular block which holds the rollers in engagement with the clutch drum.

The invention is particularly adapted for use in a cup feed sewing machine of the type shown in the patent granted to James R. Moffatt, November 13, 1917, No. 1,246,302. The improved clutch mechanism is shown as applied to this type of machine in Fig. 1 of the drawings, and is utilized for the purpose of intermittently rotating the inner feed cup. The clutch mechanism is attached to the lower end of the shaft which carries the inner feed cup. This clutch mechanism includes a drum 14 which is provided with a cylindrical recess both on the upper and lower faces thereof. Between the upper and lower cylindrical recesses there is a solid wall or partition 15 in the clutch drum 14. A set screw 16 located in this partition of the clutch drum, grips the shaft 13 and securely fastens said clutch drum to the shaft. In the lower recess as viewed in Fig. 2, there is a triangular block 17 which is similar in shape to a triangular block 18 located in the upper cylindrical recess. This triangular block 17 is rigidly secured to the clutch plate 4, which is oscillated back and forth by the link 5 which in turn is operated by the shaft 7, and the

shaft 7 is in turn operated by the eccentric 10. The triangular block 17 is secured to the clutch plate 4 by screws 21 (see Fig. 2). The clutch plate is held on the lower end of the shaft and adjacent the triangular block 17 by means of a roller 19 which is secured to the shaft 13 by a set screw 20. The clutch plate is not secured to the shaft but is free to oscillate thereon. The triangular block 18 is rigidly secured to the frame of the machine by screws similar to the screws 21 securing the block 17 to the clutch plate 4. These screws are passed through the openings 22 in the block, and the part of the frame which supports and surrounds the shaft 13 is the

- part to which this triangular block 18 is rigidly attached. This block serves to prevent retrograde movement of the clutch drum. These triangular blocks are similar 5 in construction and interchangeable, and in order that they may be made interchangeable, each block has recesses 22 extending therethrough, and at the ends of the central portions of the recesses are enlargements 23. 10 When a screw is inserted in one direction through the block, the head will rest in one recess, and when inserted in the other direction through the block, it will rest in the other recess, and thus the blocks will be properly 15 clamped in the assembling of the clutch parts. Associated with each triangular block are three rollers 24, 24, 24. These rollers are preferably hollow as indicated at 25, which is purely for the sake of lightness. Associated 20 with each roller is a spring 26. This spring is a torsional spring, that is, it is coiled intermediate its ends. One end is secured to the block by means of a screw 27. The block is provided with grooves 28, in which the end 25 of the spring is placed, and the head of the screw clamps this end of the spring against the block. This makes a very rigid support for the spring. Each spring has a relatively long arm 27' which engages a clutch roller 24. 30 This long arm 27' of the spring is, in effect, a lever, and in view of the fact that it is made strong, it operates very quickly to force the roller 24 outwardly into contact with the inner face of the clutch drum. 35 The clutch roller 24 associated with the triangular block 18 are for the purpose of gripping the drum to prevent retrograde movement thereof. The clutch rollers 24 associated with the triangular block 17 are for 40 the purpose of intermittently rotating the clutch drum and the shaft to which it is connected. This lower block 17 as has been stated, is carried by the clutch plate 4. The operation of the parts through the swinging of this clutch plate will be made clear from 45 the view in Fig. 3. When the clutch plate is moved in a clockwise direction as viewed in said figure, the flat face of the triangular block 17 will be so moved as to release its 50 grip on the roller 24 associated therewith. This is the movement of the clutch plate which enables the clutch rollers to get a new grip upon the clutch drum. The spring 26 operates to force the roller outwardly into 55 contact with the inner surface of the clutch drum, and it is the long spring lever arm 27' that accomplishes this result. It will be apparent therefore, that the spring will act very quickly and will maintain the clutch 60 rollers in contact with the drum. The movement of the clutch lever above referred to which releases the rollers from gripping engagement with the clutch drum, will roll the rollers along said surface by reason of the 65 fact that the spring continually holds the
- roller in contact with the surface of the clutch drum. It is understood, of course, that all three rollers operate precisely in the same way. This rolling of the roller along the surface of the clutch drum will continually 70 shift the position where it will grip the clutch drum and also the clutch operating triangular block, and thus distribute the wear on the roller. The inner surface of the clutch drum is preferably made slightly eccentric to the 75 axis of the shaft in order to distribute the wear on said surface. This feature, however, forms no part of the present invention, but is clearly shown and described in the patent to Dudley S. Seymour, granted January 21, 80 1919, No. 1,292,099.
- From the above it will be apparent that a clutch operating mechanism has been provided wherein the points of gripping contact, both in the mechanism for turning the feed cup and in the mechanism for holding the feed cup from turning, are constantly shifting. That is to say, the point of contact between the roller and the feed drum shifts at each retrograde movement of the operating 85 lever. The point on the roller which engages the clutch drum also shifts with each oscillation of the operating lever, by reason of the fact that the roller rolls along the surface of the feed drum. Owing to the fact that the feed drum is eccentric to the axis of oscillation of the operating lever, the point of contact between the roller and the triangular block will also shift. This all results in the 90 distributing of the wear so that there is little or no liability of the parts not gripping at the proper point with each feed cycle to insure a turning of the feed wheel a full stitch length, and to insure the holding of the feed wheel from movement when the clutch parts 95 are returning for another gripping engagement with the clutch drum. The springs which force the rollers of the clutch mechanism into contact with the surface to be gripped operate very quickly, and even 100 though the machine be driven at a speed of three thousand or more stitches per minute, which means, of course, the same number of step by step movements of the clutch mechanism per minute, there will be no slippage 105 or lost movement.
- While we have shown and described our improved clutch mechanism in connection with a feed cup, it will be understood, of course, that it may be used in connection with other rotating parts in a sewing machine where it is desired to turn said parts step by step in the same direction, and imparts step movements of uniform length thereto, and therefore, the invention is not limited to the 110 detail mechanism shown and described, but is sufficiently broad to cover all the mechanical equivalents and uses thereof as set forth in the appended claims.
- Having thus described the invention, what 115

we claim as new and desire to secure by Letters Patent, is—

1. A clutch mechanism including a clutch drum connected to said rotatable member, an oscillating flat-sided member, a roller between a flat side on said last-named member and the inner surface of said clutch drum, a spring mounted on said flat-sided member and so disposed relative to said member as to force the roller outwardly away from the flat-sided member and into rolling contact with said clutch drum whereby when said flat-sided member is oscillated in one direction, the roller will be gripped against the clutch drum and impart a forward movement thereto, and whereby when said flat-sided member is oscillated in the opposite direction, the roller will roll along the inner surface of the clutch drum thereby shifting 20 the next gripping point of the roller.

2. In a sewing machine, a rotatable member, a clutch mechanism for imparting step by step rotating movements thereto including a clutch drum connected to said rotatable member, an oscillating flat-sided member, springs mounted on said flat-sided member, a series of rollers engaging the inner wall of said clutch drum and held in spaced relation by said flat-sided member and in contact with 25 the wall of said clutch drum by said springs, said flat-sided member, clutch drum, rollers and springs being so disposed relative to each other that the gripping points of the rollers, clutch drum and flat-sided member are shifted 30 at each successive stroke of said flat-sided member.

3. In a sewing machine, a rotatable member, a clutch mechanism for imparting step by step rotating movements thereto including 40 a clutch drum connected to said rotatable member, an oscillating flat-sided member, a roller between said flat-sided member, and the inner face of said clutch drum, a spring mounted on said flat-sided member and 45 adapted to engage said roller and move said roller outwardly away from the flat-sided member into contact with said clutch drum, said flat-sided member and spring being so disposed relative to the roller and clutch 50 drum that said roller is caused to roll along the inner face of the clutch drum during the retrograde movement of the flat-sided member, and to immediately grip the inner face of said clutch drum during the forward 55 movement of said flat-sided member for imparting a step movement to said clutch drum and through said clutch drum to said rotatable member.

4. A feeding mechanism for sewing machines comprising a rotatable feed wheel, a clutch drum connected thereto, an oscillating clutch plate, a flat-sided block carried by said clutch plate and located within said drum, a roller between the flat side of the 60 plate and the inner surface of the clutch 65

drum, a lever spring for pressing said roller toward the surface of the clutch drum and holding the same continuously in contact therewith whereby when said clutch plate is moved to release the roller from gripping 70 the clutch drum, said roller will roll on said drum and thereby change the wear on the roller.

5. A feeding mechanism for sewing machines comprising a rotatable feed wheel, a clutch drum connected to said feed wheel, an oscillating clutch plate, a flat-sided block carried by said plate and located within said clutch drum, a roller between the flat side of said block and the inner face of the drum, and a spring coiled intermediate its ends and having one end therof rigidly connected to said block, the other end of said spring bearing against said roller and normally 75 forcing the same outwardly into continuous 80 contact with the clutch drum. 85

6. A feeding mechanism for sewing machines comprising a rotatable feed wheel, a clutch drum connected to said feed wheel, an oscillating clutch plate, a flat-sided block carried by said plate and located within said clutch drum, a roller between the flat side of said block and the inner face of the drum, a spring wire bent intermediate the ends and again coiled intermediate its length after 90 being bent, so as to form two extending lever arms, said block having grooves formed therein adapted to receive the ends of the spring wire, and a headed screw for clamping the wire in said grooves, said spring being 95 arranged so that the free spring lever arm thereof bears against the roller and normally forces said roller out into continuous contact 100 with said clutch drum. 105

7. A feeding mechanism for sewing machines comprising a rotatable feed wheel, a shaft connected to said feed wheel and supporting the same, a clutch drum mounted on said shaft, a clutch plate mounted on said shaft and freely oscillating thereon, a block secured to said clutch plate and extending into said clutch drum, said block having a series of flat faces thereon, a roller between each flat face and the inner surface of said clutch drum, a spring for each roller, said spring being coiled so as to form an extended spring lever arm, said springs being mounted on said block and engaging the respective rollers so as to force the rollers outwardly 110 into contact with the clutch drum. 115

8. A sewing machine including in combination a rotatable feed wheel, a clutch drum connected thereto, an oscillating plate at one end of said drum and having a flat-sided block extending into the adjacent end of the clutch drum, a flat-sided block secured to the frame of the machine and extending into the other end of the clutch drum, rollers between said blocks and the inner face of the clutch drum, a spring associated with each roller 120 125

and having a relatively long spring arm for forcing the rollers outwardly into contact with the clutch drum, whereby the oscillation of the block connected to the clutch plate ⁵ will intermittently rotate said feed wheel in one direction, and whereby the block at the other side of the clutch drum operating

through the rollers associated therewith will prevent retrograde movement of said clutch drum.
